COMBINATION BROOCH AND DRESS CLIP

Louis Mazer, New York, N. Y.

Application August 28, 1937, Serial No. 161,405

7 Claims. (Cl. 63—20)

My present invention is concerned with combination brooches and dress clips of the type in which a pair of ornamental dress clips are releasably mounted on a carrier structure to form a brooch.

Among the objects of the invention are to provide an article of the above type which is relatively inexpensive in construction, easily assembled and disassembled for the use of the device 10 alternatively as a brooch or as a pair of clips.

Another object is to provide a device of the above type in which the dress clips in the brooch assembly are secure against any shifting or looseness, and the dress clips themselves are securely locked against opening of the jaw members thereof.

In the accompanying drawing, on which is shown one of various possible embodiments of the several features of the invention,

20 Fig. 1 is a rear plan view of the assembled brooch structure,

Fig. 2 is a view in longitudinal cross-section taken of line 2—2 of Fig. 1;

25 Fig. 3 is a view in transverse cross-section taken of line 3—3 of Fig. 1;

Fig. 4 is a view similar to Fig. 3 taken of line 4—4 of Fig. 1;

Fig. 5 is a detail sectional view taken of line 5—5 of Fig. 1;

30 Fig. 6 is a perspective view of the carrier element of the brooch and

Fig. 7 is a perspective view in reversed position of one of the dress clips.

Referring to the drawing the brooch shown 35 assembled in Figs. 1 and 2 is made up of the carrier element shown in perspective in Fig. 6 and a pair of the dress clips shown in perspective in Fig. 7.

The dress clips are generally conventional in 40 appearance with modifications to be now set forth. Each dress clip includes a pair of jaws including an ornamental front jaw 10 which may be studded with jewels or imitation jewels and a rear jaw 11 preferably of stamped metal, which 45 is hinged to the front jaw. Preferably the rear jaw is of open construction and has turned in tangs 12 near the free end thereof for penetrating the garment on which the article is to be worn as a dress clip.

50 Preferably the rear jaw also has a longitudinal spring tongue 13 at the rear or hinged end thereof which is cut out of the main structure of said jaw and spaced therefrom by longitudinal slots 14 which serve the purpose to be hereinafter set forth. The front or ornamental jaws each have a bracket 15 attached thereto, provided with lateral hinge ears 16, each mounting a short pin 55 tle 17 encircled by the lateral hinge loops 18 of the rear jaw 11.

60 Integral with the bracket 15 and between the

hinge ears 16 thereof, is an upstanding spring tensioning ledge 19 over which the free end of the spring tongue 13 rides, thereby to snap the jaws from any intermediate position either to closed or to wide open position in well understood manner.

As best shown in Fig. 3 the hinge loops 18 are spaced from the front ornamental jaw 10 of the clip to determine a small opening 20 between said front and said hinge member which is 10 flanked by the lateral edge of the tensioning ledge 19 on one side and the hinge ear 16 on the other, and which serves a purpose to be described hereinafter.

The carrier member for two of the dress clips, 15 just described preferably comprises a bar 21 having a conventional fastening pin 22 hinged to ears 23 thereon near one end thereof and provided with a pin keeper 24 of conventional construction near the other end thereof.

20 The carrier member may include, as best shown in Fig. 6 a bar 25 parallel to the bar 21 and rigidly connected as a unitary structure therewith, as for instance by connecting bridges 26 punched out as an integral stamping with the 25 two bars. Bar 25 is widened at its ends 27 and has rigid therewith two down-turned lateral tongues 28, each with a slot 29 to provide a hook, said hooks facing outwardly and the slots thereof being of width equal to the thickness of the clip 30 jaw 11.

35 Preferably the carrier member also has down-turned lateral tongues 29' at the middle thereof which protrude downward to a depth greater than that of the hooks 28. One of the tongues 35 has a T head bent at right angles to the tongue and affording longitudinal dowel lugs 30 which extend parallel to the bar 21.

The spacing between the pairs of hook tongue 28 and between the pair of tongues 29 is equal 40 to the width of the spring tongues 13 on the dress clips.

45 It will readily be seen that for assembly of the brooch the hook conformations 28 of the carrier are simply pressed downward into the slots 14 flanking the spring tongue 13 of the dress clip and then slid toward the other end of the clip, to cause the hooks to underlie the rear jaw 11 which is gripped thereby as best shown in Fig. 2. In this operation, the dowel lug 30 will enter and 50 be tightly lodged in the gap 20. In exactly the same manner the companion clip is mounted upon the other end of the carrier as shown in Figs. 1 and 2 with the edges of the ornamental front jaws of the clips in abutting relationship as 55 shown. The middle tongues 29' of the carrier in the assembly set forth straddle the lateral edges of the free ends of spring tongues 13 to aid in the security of assembly.

60 By the construction set forth, not only are 60

the dress clips securely mounted upon the carrier but the carrier serves to lock each clip in closed position. Each clip is clasped as it were and locked closed by the dowel lug 30 extending under the hinge element thereof and the hooks 28 through the rear jaws and over the hinge element thereof. The assembly serves as a brooch the composite or knock-down character of which is not apparent to the casual observer. The mode of disassembly of the brooch is apparent from the description above set forth.

It will be understood that while it is preferred as set forth, to form the clip mounting instrumentalities of the carrier on a bar parallel to, yet integral with the fastening pin carrying bar, such instrumentalities could be formed directly on said latter bar, and certain of the claims have been drafted to embrace such structure within their scope.

20. It is also understood that though the middle tongues of the carrier are a desirable aid to security of attachment, a reasonably satisfactory construction would be possible with the omission thereof, or with the omission of the dowel lugs 25 30, or if desired said lugs could be provided on each of the lateral fingers 29' instead of on only one of them as shown. It is also understood that while the hook elements at the ends of the carrier are preferably disposed in pairs to grip the rear jaws of the spring clips, less or more than 30 two of such hooks could be used advantageously.

It will thus be seen that there is herein described an article in which the several features of this invention are embodied, and which article in its action attains the various objects of the invention and is well suited to meet the requirements of practical use.

As many changes could be made in the above article and many apparently widely different embodiments of this invention could be made 40 without departing from the scope thereof, it is intended that all matter contained in the above description or shown in the accompanying drawing shall be interpreted as illustrative and not in a limiting sense.

45 Having thus described my invention, what I claim as new and desire to secure by Letters Patent is:

1. A brooch comprising a carrier including a 50 fastening-pin carrying bar, a pair of hook members rigid with said carrier near the ends thereof and facing outwardly therefrom, and dowel members located centrally with respect to said bar, and a pair of dress clips each having an ornamental front jaw and a coacting back jaw, said 55 back jaw having longitudinal slots for accommodating the end hook members of the carrier and gaps near the respective hinges thereof for accommodating the dowel members firmly yet releasably to mount the clips in position upon the carrier.

2. A brooch comprising a carrier bar having rigidly mounted near each end thereof, a pair of 60 parallel hook conformations facing outwardly, said bar having rigid with respect thereto and midway between the ends thereof a pair of down-turned fingers, a pair of dress clips each comprising an ornamental front jaw and a back jaw hinged thereto the latter including a spring 65 tongue intermediate the hinge mounts thereof said tongues defining longitudinal slots for accommodating the hook conformations of the carrier, the down-turned fingers confining the lat-

eral edges at the free ends of the respective spring tongues in the assembled brooch.

3. A brooch comprising a carrier bar having rigidly mounted near each end thereof a pair of parallel downturned hook conformations facing outwardly, said bar having downturned fingers rigid with respect thereto and midway between the ends thereof, a pair of dress clips each comprising an ornamental front jaw and a back jaw, the latter including a spring tongue intermediate the hinge mounts thereof, spaced by longitudinal slots from the body of the jaw and serving to accommodate the hooks of the carrier, the downturned fingers straddling the lateral edges of the free ends of the respective spring tongues in the 15 assembled brooch, one of said downturned fingers of the carrier having longitudinally extending dowel lugs the hinging portions of the brooch presenting clearance with respect to the front jaw thereof snugly to accommodate said dowel 20 lugs.

4. A brooch comprising a pair of spring dress clips including a front jaw and a back jaw, spring means adapted to maintain the jaws alternatively in closed or in open position, and a 25 carrier bar for supporting said clips in cooperative engagement to determine the brooch, said bar having means hooking under as well as means hooking over the hinge members of the respective clips and serving to lock the clips 30 against relative transverse movement in closed position while assembled as parts of the brooch while permitting said clips to be separated endwise.

5. In a brooch of the type comprising a carrier 35 for a pair of dress clips to be releasably assembled thereon; a carrier construction which includes a bar having a fastening pin and two pairs of hooks disposed near the ends of said bar in planes at right angles thereto, rigid therewith 40 and facing outwardly and centrally disposed fingers substantially parallel to the respective hooks, one of said fingers having outwardly protruding dowel lugs.

6. A brooch comprising a bar having a hinged 45 pin and a pin keeper, a carrier bar conformation parallel to said bar and rigidly connected thereto and unitary therewith, said carrier bar including hook structures rigid therewith, extending in downturned pairs outwardly from 50 near the opposite ends thereof and also including median fingers parallel to said hooks, one of said fingers having outwardly extending dowel lugs.

7. A brooch comprising a bar carrying a 55 mounting pin and a keeper therefor, a clip carrier bar parallel to said first bar and rigidly conformed as a unit therewith, said carrier bar having hook conformations protruding from near the opposite ends thereof and facing outwardly 60 and fingers at the middle of said carrier bar with outwardly extending dowel lugs, a pair of dress clips including ornamental front jaws and metal back jaws, the latter each having a central spring tongue, tensioning ledges on the front jaw 65 coacting with said spring tongues, said spring tongues affording lateral gaps for accommodating the respective hook conformations of the carrier bar and hinge elements at opposite sides of the tensioning ledge spaced from the front 70 jaws of the clips, and accommodating the dowel lugs on the carrier bar.

LOUIS MAZER.
